LOCK TYPE SHINGLE

John V. Donahue, Anderson, Ind.

Application May 31, 1930, Serial No. 458,412

4 Claims. (CL. 108—7)

This invention relates to roofing shingles of the interlocking type and has for its primary objects the provision of a form of composition shingle which may be produced with no waste; which may be laid to give any desired degree of exposure; which may interlock with adjacent shingles to prevent the butt ends from blowing upwardly; which can be applied to a roof with relatively little effort and at a comparatively low labor cost; which can be applied to circular roofs equally as well as to straight roofs; and the material cost of which may be but about twenty per cent more than roll roofing.

Other objects reside in the individual effect of the entire roof as produced by the assembled shingles and in the means for determining the line of the butt ends across the roof. These and additional objects will become apparent in the following description of the invention as illustrated by the accompanying drawing, in which

Fig. 1 is a top plan view of a shingle embodying my invention;

Fig. 2, a plan view in reduced scale of a sheet of composition roofing material on which is indicated the manner of cutting the shingles therefrom;

Fig. 3, a top plan view of a group of shingles laid to give a "single" covering;

Fig. 4, a top plan view of a group of shingles laid to give a double covering; and

Fig. 5, a top plan view of a group of shingles as applied to a circular roof.

Like characters of reference indicate like parts in the several views in the drawing.

Referring first to Fig. 1, I cut a shingle 10, substantially rectangular in shape, one particular style being cut to be sixteen inches high and eighteen inches long, the upper corners forming ninety degree angles. The right hand vertical edge of the shingle is not cut entirely down to the butt end *a*, but a flap 11 is left at the lower end to have an upper edge sloping upwardly and toward the vertical edge of the shingle and a slit 12 is cut vertically downwardly from the juncture of this upper flap edge and the shingle vertical edge. The lower edge of the flap 11 is a horizontal continuation of the butt end *a* of the shingle 10. The right hand end of the flap 11 is bounded by a vertical line, and the slit 12 terminates substantially at or a trifle below the level of the top end of that vertical edge, which point is the juncture of the outer end of the upper sloping edge of the flap therewith. The lower end of the slit 12 terminates in a short

transverse slit 14 as a means for preventing the tearing downwardly of the slit from its lower end.

The left hand lower corner of the shingle 10 has a section removed therefrom which corresponds exactly in dimensions to the flap 11. As indicated in Fig. 2, by reason of the flap 11 being of the same dimensions as the removed section, one shingle 10 may be cut right after another along the length of the strip of roofing 13, the flap 11 of the first shingle 10 being cut from the lower corner of the next succeeding shingle without any waste whatsoever between vertical edges of the shingles, and, since the upper and lower edges of the shingles are parallel one to the other, there is no waste horizontally between upper and lower rows of shingles being cut from the strip, and similarly, there is no waste along the edges of the strip since the width of the strip of roofing employed is proportioned to equal the combined heights of the rows of shingles to be cut therefrom.

Referring now to Fig. 3, where a "single ply" roof is to be produced, a shingle 10 is positioned and a single nail 15 is driven through the flap 11 into the roof sheathing thereunder. The right hand vertical edge of the shingle 10 is then raised slightly and the left hand vertical edge of a shingle 10' is inserted under that raised edge and the shingle 10' is then pulled downwardly and toward the shingle 10 to have the apex of the reentering angle in the cut away section of the shingle 10' positioned at the lower end of the slit 12, whereupon the butt edge of the shingle 10' will align with the butt edge of the shingle 10, and a nail 16 is then driven through the flap 12' of the shingle 10'. Similarly, the shingle 10' is laid and a nail 17 placed through the flap 11' thereof. The next above row of shingles is laid in the same manner but with the vertical edges of the shingles moved over to be half way between the right hand vertical edges of the shingles in the row therebelow. The upper row is laid to have the juncture of the top edge of the flap 11 and the vertical edge of the shingle on the line of the top edges of the shingles of the row next below.

In Fig. 4, the shingles are shown as having been laid to give a "two ply" roof in that there is always a thickness of two shingles over the sheathing instead of the minimum of one thickness as results in laying the shingles as above described and as shown in Fig. 3. To facilitate the laying of the shingles with less exposure, the right hand vertical edges of the shingles may be provided with a notch 18 spaced upwardly from

the butt ends the distance of the exposure desired, and the rows of shingle across the roof may be aligned readily by placing the butt ends of the upper row at the notches in the shingles in 5 the row below.

The shingle is well adapted for use in laying circular roofs as indicated in Fig. 5. A shingle 10' may be rocked upwardly to have its left hand vertical edge rocked farther back under the over-lapping right hand vertical edge of the preceding shingle 10 so that the butt end may be carried around on the desired circle. The locking feature in such cases does not interfere and the roof layer does not have to stop and cut and fit 15 shingles as has heretofore been required in other types. The circular shape is simply met by varying the slope of the vertical edges.

While I have here shown and described my invention in the one best form as now known to 20 me, it is entirely obvious that structural changes may be made without departing from the spirit of the invention, and I, therefore do not desire to be limited to that precise form nor any more 25 than may be required by the following claims.

25 I claim:

1. A shingle having the general shape of a rectangle, a nail flap extending laterally from the lower right hand corner of the shingle, and having a section removed from the other lower 30 corner to form a reentering angle therein, said shingle having a slit cut downwardly from its vertical edge partly severing said flap from the shingle, said slit having its lower end terminating on the same horizontal line as the apex of 35 said reentering angle.

2. A roof comprising a plurality of composition shingles, each of said shingles being substantially rectangular in shape having a nail flap extending laterally from the lower right corner of the 40 shingle, and having a notch cut out of the lower left hand corner, one of said shingles having a nail through said flap, and the next horizontally adjacent shingle having its left vertical edge above said notch inserted under the right vertical edge of the first shingle down to said flap and having the notch in the second shingle placed 45 around the upper juncture of the flap with the first shingle to permit the butt end of the second shingle to be aligned in the same line including the butt end of the first shingle, and having a nail through the flap of the second shingle, and succeeding shingles similarly assembled one with the other to form a continuous row across the roof, and a second row of shingles overlapping the 50 first row from above.

3. A roof comprising a plurality of composition

shingles, each of said shingles being substantially rectangular in shape having a nail flap extending laterally from the lower right corner of the shingle, and having a notch cut out of the lower left hand corner, one of said shingles having a nail through said flap, and the next horizontally adjacent shingle having its left vertical edge above said notch inserted under the right vertical edge of the first shingle down to said flap and having the notch in the second shingle placed around the upper juncture of the flap with the first shingle to permit the butt end of the second shingle to be aligned in the same line including the butt end of the first shingle, and having a nail through the flap of the second shingle, and succeeding shingles similarly assembled one with the other to form a continuous row across the roof, and a second row of shingles overlapping the first row from above. 5

4. A roof comprising a plurality of composition shingles, each of said shingles being substantially rectangular in shape having a nail flap extending laterally from the lower right corner of the shingle, the under line of the flap being a continuation of the under line of the shingle, said flap having a slit entering from its upper 30 edge and extending vertically downward from the right edge of the shingle, and having the left lower corner cut away to leave a notch therein, defined by an upper edge sloping inwardly and downwardly from the left edge of the shingle to 35 an intersecting edge extending vertically upwardly from the lower shingle edge, said intersecting edge having a length approximately the same as the width of said flap from the bottom edge to the lower end of said slit, one of said shingles 40 having a nail through said flap near the lower edge thereof, and the next horizontally adjacent shingle having its left vertical edge inserted under the right vertical edge of the first shingle to have the apex of said notch positioned at the bottom of said slit with the flap of the first shingle under the second shingle to have the butt edge of the second shingle aligned with the butt edge of the first shingle, and having a nail through the flap of the second shingle, and succeeding shingles 50 similarly assembled one with the other to form a continuous row across the roof, and a second row of shingles similarly placed overlapping the first row from above. 10 15 20 25 30 35 40 45 50
